FOLDING UMBRELLA

William A. Heilmann, Orange, and William Schultz, Kearney, N. J., assignors to Newark Rivet Works, Newark, N. J., a corporation of New Jersey

Application March 23, 1938, Serial No. 197,574

6 Claims. (Cl. 135—25)

This invention relates, generally, to improvements in umbrellas, parasols and the like, which are adapted to be collapsed and folded, when closed, to a substantially reduced length and compact bulk, whereby, when so conditioned, the same may be easily stored and carried within a traveling bag or other luggage carrier.

This invention has for an object to provide a novel improved collapsible umbrella structure including a staff or rod comprising telescopic sections and a novel arrangement of latching detent devices operative to optionally retain the umbrella structure in either open condition for use, normally closed condition for hand carriage, or in collapsed and folded condition for storage.

Another object of the invention is to provide, in connection with the staff or rod of the structure, a novel handle means so constructed and related to the telescopic sections of said staff or rod, and to the latching detent devices of the latter, that it may be utilized to embrace and hold the umbrella rib elements against opening movement both when normally closed for hand carriage, as well as when collapsed and folded for storage.

Another object of the invention is to provide a very rigid, strong and durable staff or rod structure for the umbrella comprising telescopic tubular sections having inter-engaging guide means which will permit relative sliding movements thereof while at the same time preventing rotative displacement of one section relative to the other so that properly aligned cooperative relation of the elements of the latching detent devices is maintained at all times.

Other and more specific objects of this invention, not at this time more particularly enumerated, will be understood from the following detailed description of the same.

Illustrative embodiments of this invention are shown in the accompanying drawings, in which:

Fig. 1 is an elevational view, with portions broken away, showing the umbrella structure, according to this invention, in its open condition; Fig. 2 is an elevational view of the umbrella structure as closed for hand carriage; and Fig. 3 is an elevational view of the same as fully collapsed and folded in to a small bulk of greatly reduced length ready for storage within a traveling bag or other storage compartment.

Fig. 4 is in part a side elevation and in part a longitudinal sectional view of the umbrella staff or rod, and rib structure supported thereby, as extended to arrange the umbrella in open or service condition; Fig. 5 is a longitudinal sec-

tional view, taken on line 5—5 in Fig. 4; Fig. 6 is a view similar to that of Fig. 5, but showing the rib structure closed; Fig. 7 is a fragmentary longitudinal section, similar to Fig. 6, but showing the staff or rod partially collapsed to engage the handle member in embracing and holding relation to the free ends of the closed ribs, thus arranging the umbrella in normal closed condition for hand carriage as shown in Fig. 2; and Fig. 8 is a fragmentary longitudinal section showing the staff fully collapsed and the rib structure folded, with portions of the latter engaged and embraced by the handle member, thus arranging the umbrella in collapsed and folded condition for storage, as shown in Fig. 3.

Fig. 9 is an enlarged fragmentary longitudinal section of the staff or rod members showing the interengaged guide means with which the same are provided; and Fig. 10 is a transverse section thereof, taken on line 10—10 in Fig. 9.

Fig. 11 is a view similar to that shown in Fig. 1, but illustrating the umbrella rib structure as modified to provide the "Bombay" form of umbrella spread; Fig. 12 is a fragmentary face view of a "Bombay" effect rib element, and Fig. 13 is an edge elevation of the latter.

Similar characters of reference are employed in the above described views, to indicate corresponding parts.

The novel umbrella structure according to this invention includes a collapsible central rod or staff comprising upper and lower tubular rod sections 15 and 16, so arranged that the lower rod section 16 slides telescopically into the upper rod section 15. The lower rod section is provided with indented longitudinal guide channels 17 extending along opposite sides thereof. The upper rod section is provided on opposite sides thereof and adjacent to its lower extremity with guide projections 18 which slidably ride in the guide channels of said lower rod section, thus permitting relative longitudinal movements of said rod sections, but preventing relative rotative movements thereof. The guide channels 17 of the lower rod section terminate short of the upper end thereof, thus providing stop shoulders 19 engageable by said guide projections 18 so as to limit the extended position of said lower rod section relative to the upper rod section.

Affixed to the upper end portion of said upper rod section 15 is a crown member 20 to which are pivotally attached the inner extremities of radiating collapsible rib structures for supporting the umbrella cover or top 21. Each such rib structure comprises inner and outer rib members

- 22 and 23. These rib members are connected together end to end by a suitably constructed joint member 24, which is adapted, under proper conditions, to permit the outer member 23 to fold in one direction backwardly over and upon the inner member 22. The outer members 23 may, if desired, be made with a flat flexible center strip 25 for obtaining the "Bombay" type of umbrella top spread (see Figs. 11, 12 and 13).
- 10 Mounted to slide longitudinally upon said upper rod section 15 is a runner 26, to which are pivotally connected the lower ends of rib stays or braces 27, the upper ends of which are pivotally connected to the inner rib members 22 at suitable points intermediate the ends of the latter.
- 15 The upper rod section 15 is provided with a novel form of depressible stop spring to engage and hold the runner 26 in its upwardly moved rib structure spreading position, whereby the umbrella is arranged in its open or service position, as shown in Figs. 1 and 11. Said depressible stop spring comprises an upwardly projected spring leaf or finger 28 which is struck out bodily from the side wall of the tubular body of said upper rod section 15. When the runner is moved upwardly over said upper rod section to rib structure spreading position, the same will ride over said spring leaf or finger 28, which yields to its passage, but will, by virtue of its inherent resiliency, 25 spring outwardly and behind the runner so as to oppose and engage the lower end flange 29 of the latter, thus holding said runner in raised rib structure spreading position. When it is desired to close the umbrella, the spring leaf 28 may be 30 inwardly depressed by the operator's finger, so as to permit the runner to be slid downwardly thereover and then along the upper rod section 15, thereby to swing down the rib structure to umbrella closing position.
- 35 40 Struck from the body of said leaf spring 28, intermediate its lower fixed end and its upper free end, is a rounded projection or tit 30 which projects into the bore of said tubular upper rod section to lie in the path of movement therewith of the lower rod section 16. When the lower rod section 16 is slid inwardly and upwardly through the upper rod section 15, the upper end portion of the former will engage and push outwardly upon said tit 30, to thereby positively move the spring leaf 28 to its outswung normal position. The effect of this is to compensate for any possible loss or relaxation of resiliency which might be suffered by the leaf spring under frequent applications of inward releasing pressure thereupon.
- 45 50 55 The upper end portion of the tubular lower rod section 16 is provided with a suitably located opening 31 which, when the lower rod section is pushed upwardly into the upper rod section to the limit of its upward movement, may spring over said tit 30, and by such engagement yieldably retain the rod sections thus telescopically closed together.
- 60 65 70 75 Affixed to the free extremity of said lower rod section 16 is a handle member or knob 32 of any desired ornamental shape. This handle member or knob 32 is provided in its upper end with an upwardly open recess 33 concentric to said lower rod section, the same being adapted, at proper times, to embrace portions of the closed or collapsed rib structure in the manner and for the purposes to be subsequently explained. It is frequently desirable to provide the handle member or knob 32 with an extending flexible carrying loop 34, through which the hand or arm of the user may be engaged for conveniently carrying

the umbrella about in ordinary closed condition. To conveniently attach said loop 34 to the handle member or knob 32, the latter may be provided with openings through which the loop ends may be passed into the interior of the recess 33, and then knotted, as shown at 35, to anchor said ends to the handle member or knob. It will be understood however that the carrying loop 34 may be attached to the handle member or knob in any other suitable or convenient manner.

One of the important features of this invention resides in a novel arrangement and construction of latching detent means for positioning and holding the tubular rod sections 15 and 16 in various relative positions accordingly as the umbrella is arranged in opened condition for use, in normally closed condition for hand carrying, or in completely collapsed and compactly folded condition for storage. Said latching detent means includes a primary latching detent or dog 36 having a resilient tail-piece 37. Said detent or dog 36 is secured within the upper end portion of said lower rod section 16 by anchoring its tail-piece 37 to the wall thereof, as by a riveting projection 38, and so that the operative portion of said detent or dog 36 is yieldably projected outwardly through an opening 39 provided in the wall of said lower rod section. An end of said detent or dog 36, which extends at a right angle to or transversely of the longitudinal axis 30 of the rod sections 15-16, provides a positive or locking stop shoulder 40. Formed at the outer longitudinal marginal portion of said detent or dog 36, to extend outwardly beyond said locking stop shoulder 40 is a stop nosing 41, having chamfered end portions providing an upper cam end 42 and a lower cam end 43. Formed in the wall of the lower end portion of said upper rod section 15 is a main latch slot 44, which registers in alignment with said detent or dog 36 when the rod sections 15-16 are relatively extended to maximum staff forming length. Also formed in the wall of the lower end portion of said upper rod section 15, in a position upwardly spaced from but aligned with said main latch slot 44, is a second latch slot 45 for cooperation at proper times with said primary latching detent or dog 36. The latching detent means further includes a secondary latching detent or dog 46 having a resilient tail-piece 47. Said secondary detent or dog 46 is secured within the lower end portion of said lower rod section 16 by anchoring its tail-piece 47 to the wall thereof, as by a riveting projection 48, and so that the operative portion of said detent or dog 46 is yieldably projected outwardly through an opening 49 provided in the wall of said lower rod section. Formed at the outwardly projecting longitudinal marginal portion of said detent or dog 46 is a stop nosing 50 having chamfered end portions providing an upper cam end 51 and a lower cam end 52.

In the various manipulations of the umbrella the novel latching detent means operates as follows:

When the umbrella is opened for use, as shown in Figs. 1 and 11, and the staff thereof extended to full length for supporting the same in such open condition, the lower rod section 16 is pulled downwardly and outwardly relative to the upper rod section until the limit of relative extension 70 of said rod sections is determined by the engagement of the guide projection 18 of the upper rod section with the stop shoulder 19 of the lower rod section. When the rod sections 15-16 are thus extended, the main latch slot 44 is aligned 75

or in register with the primary detent or dog 36, so that the latter, under the projecting tension of its tail-piece 37, is projected to maximum extent through the main latch slot 44, and thus to a position in which its square locking shoulder 40 is opposed to the upper end of said main latch slot 44, and consequently by abutment against said slot end prevents any upward sliding movement of the lower rod section 16 into the upper rod section 15. In other words, said rod sections are thus interlocked in their extended relation against accidental collapse. When the primary detent or dog 36 is thus disposed its stop nosing 41 projects freely outward beyond the external surface of the upper rod section 15 (see Figs. 4 and 5).

When it is desired to close the umbrella, the operator depresses the spring leaf 28 to free the runner 26 for downward movement. As the downwardly moved runner approaches the lower limit of its movement, it engages and slides over the upper cam end 42 of the freely projecting stop nosing 41 thus pressing said primary detent or dog 36 against the tension of its tail-piece 37, and thereby withdraws the square locking shoulder 40 out of said main latch slot 44, and disposes the stop nosing 41 within the latter, with the upper cam end 42 opposed to the upper end thereof (see Fig. 6). Such relation of the stop nosing 41 to the main latch slot 44 is sufficient to resist relative collapsing movement of extended rod sections in the absence of manually applied overcoming force.

When the umbrella is thus closed, the down swung rib structure disposes the tips T thereof adjacently above the handle member or knob 32. To hold the rib structure in such normal closed disposition, the tips T are gathered together and opposed to the recess 33, whereupon the handle member or knob is pushed inwardly so as to embrace said tips T within the recess (see Fig. 7). This inward movement of the handle member or knob is transmitted to the lower rod section 16 which is thereby caused to move partially into the upper rod section 15. Such inward movement of the lower rod section 16 carries the upper cam end 42 of the stop nosing 41 of the primary detent or dog 36 forcibly against the upper end of the main latch slot 44, thus further depressing said primary detent or dog and permitting the stop nosing 41 thereof to ride out of the main latch slot 44, and to be thence carried upwardly into register with the second latch slot 45 into which it is thrust under the tension of the resilient tail-piece 37 of the primary detent or dog 36 (see Fig. 7). Such relation of the stop nosing 41 to the second latch slot is sufficient to resist any further relative movement of the rod sections 15-16 in the absence of manually applied overcoming force, and consequently the closed umbrella with its handle member or knob positioned in embracing and holding relation to the rib structure tips T, may be carried about by hand, as e. g. by suspending the same by means of the loop 34. When it is again desired to raise or open the umbrella, the handle member or knob 32 is first pulled downward to disengage the rib structure tips T. Such operation slides outward the lower rod section, the initial outward movement of which carries the lower cam end 43 of the stop nosing 41 forcibly against the lower end of the second latch slot, thereby depressing said primary detent or dog and permitting the stop nosing to ride out of the second latch slot, and thence to be moved downwardly until again

aligned with the main latch slot 44 for projection outwardly therethrough, whereupon the runner 26, when slid upwardly, again permits full outward projection of the detent or dog 36 with its square locking shoulder again opposed to the upper end of said main latch slot 44 as and for the purposes hereinbefore described.

To collapse the umbrella to compactly folded condition for storage in a traveling bag or other limited storage space, the umbrella is first closed 10 by releasing and lowering the runner 26 to thereby swing down the rib structure, whereupon the outer rib members 23 are turned or doubled back upon the inner rib members 22 thus folding the outer portions of the umbrella top or cover 21 15 upon itself, as shown in Fig. 3. The adjoined end portions of the rib structure at the joint members 24 are now directed toward the handle member or knob 32, and may be gathered together so as to be received and held within the 20 recess 33 of the handle member or knob, when the latter is moved upward by sliding inwardly the lower rod section relative to the upper rod section to completely telescopically collapsed condition. Such relative movement of said rod sections, carries the lower end portion of the upper rod section 15 forcibly against the upper cam end 51 of the nosing 50 of said secondary detent or dog 46, thus inwardly depressing the latter, to permit the upper rod section to ride over said 30 nosing 50 until the latter registers with the main latch slot 44 of the former into which it is projected. Such relation of the stop nosing 50 to said main latch slot 44 is sufficient to resist relative movement of the rod sections 15-16 in the 35 absence of manually applied overcoming force, and consequently the umbrella parts are retained in fully collapsed and folded relation desirable for storage (see Figs. 3 and 8). When it is again desired to use the umbrella, the handle member or 40 knob is pulled downward to disengage the folded rib structure. The accompanying outward sliding movement of the lower rod section 16 relative to the upper rod section 15 carries the lower end cam 52 of the stop nosing 50 forcibly against 45 the lower end of the main latch slot 44, thereby permitting the stop nosing 50 to ride out of the latter and thus freeing the rod sections for movement back to normal extended relation.

We are aware that various changes could be 50 made in the above described constructions, and many apparently widely different embodiments of this invention could be made without departing from the scope thereof as defined in the following claims. It is therefore intended that all 55 matter contained in the above description or shown in the accompanying drawings shall be interpreted as illustrative and not in a limiting sense.

We claim:

1. In a collapsible umbrella, a staff comprising upper and lower rod sections arranged in telescopic sliding relation and having cooperating guide means to retain the same against relative rotative movement, a collapsible rib structure including stay portions, said rib structure being pivotally connected with the upper end of said upper rod section, a runner operatively connected with said stay portions and slidably mounted on said upper rod section, a handle member affixed 70 to the free end of said lower rod section, said handle member having means to engage and hold portions of said rib structure when the latter occupies given collapsed positions, latching detent means carried by said lower rod section, said 75

- upper rod section having a plurality of latch slots for selective cooperation with said detent means when said rod sections are variously relatively disposed either in full extended position with the rib structure open or in positions to engage the handle member means in holding relation to the rib structure when the latter occupies given collapsed positions.
2. In a collapsible umbrella, a staff comprising upper and lower rod sections arranged in telescopic sliding relation and having cooperating guide means to retain the same against relative rotative movement, a collapsible rib-structure including stay portions, said rib structure being pivotally connected with the upper end of said upper rod section, a runner operatively connected with said stay portions and slidably mounted on said upper rod section, a handle member affixed to the free end of said lower rod section, said handle member having means to engage and hold portions of said rib structure when the latter are collapsed, a latching detent yieldably projected from a side of said lower rod section adjacent to its upper end, said upper rod section having latch slots adjacent to its lower end for cooperation with said latching detent, said slots comprising a main latch slot and a second latch slot aligned with but spaced above said main latch slot, said latching detent having a transverse locking stop shoulder and at its outer side a stop nosing projecting beyond said shoulder, and said stop nosing having cam ends at its respective extremities, said latching detent being adapted to be projected through said main latch slot when said lower rod section is fully extended relative to said upper rod section, to thereby oppose said locking stop shoulder to the adjacent end of said main latch slot and to project said stop nosing beyond the exterior surface of said upper rod section subject to engagement of a cam end thereof by the lower runner to automatically depress said latching detent to remove its locking stop shoulder from said main slot and thereby release said lower rod section for upward movement to carry said handle member means into holding relation to the collapsed rib structure and to move the stop nosing of the latching detent into engaging relation to said second latch slot.
3. In a collapsible umbrella as defined in claim 2, a depressible stop means for holding the runner in upwardly moved rib structure spreading position, comprising a spring leaf integral with and struck out of the wall of said upper rod sec-
- tion, a rounded tit inwardly struck from the body of said spring leaf for projection into the interior of said upper rod section and into the path of movement of said lower rod section relative to said upper rod section.
4. In a collapsible umbrella as defined in claim 2, a depressible stop means for holding the runner in upwardly moved rib structure spreading position, comprising a spring leaf integral with and struck out of the wall of said upper rod section, a rounded tit inwardly struck from the body of said spring leaf for projection into the interior of said rod section and into the path of movement of said lower rod section relative to said upper rod section, and said lower rod section having an opening in the wall thereof adjacent to its upper end, said opening being adapted to receive said tit to releasably retain said lower rod section in its inwardly disposed relation to said upper rod section.
5. In an umbrella, a staff comprising upper and lower rod sections arranged in telescopic sliding relation, a rib structure controlling runner slidably movable on said upper rod section, a depressible stop means for holding said runner in upwardly moved rib structure spreading relation, comprising a spring leaf integral with and struck out of the wall of said upper rod section, and a rounded tit inwardly struck from the body of said spring leaf for projection into the interior of said upper rod section and into the path of movement of said lower rod section relative to said upper rod section.
6. In an umbrella, a staff comprising upper and lower rod sections arranged in telescopic sliding relation, a rib structure controlling runner slidably movable on said upper rod section, a depressible stop means for holding said runner in upwardly moved rib structure spreading relation, comprising a spring leaf integral with and struck out of the wall of said upper rod section, a rounded tit inwardly struck from the body of said spring leaf for projection into the interior of said upper rod section and into the path of movement of said lower rod section relative to said upper rod section, and said lower rod section having an opening in the wall thereof adjacent to its upper runner end, said opening being adapted to receive said tit to releasably retain said lower rod section in its inwardly disposed relation to said upper rod section.
